ELECTRIC ADDING MACHINE

Thomas McGourty, P.O. Box 134,
Norfolk, Conn. 06058

Filed Oct. 24, 1967, Ser. No. 9,144

Term of patent 14 years

(Cl. D64—11)

FIG. 1

FIG. 2

FIG. 1 is a perspective view, viewed from the front of an electric adding machine showing my new design; and

FIG. 2 is a perspective view, viewed from the rear.

The essential features of the design reside in the portions shown in solid lines; conventional details being shown in broken lines. The bottom surface of the design is plain.

I claim:

The ornamental design for an electric adding machine, as shown and described.
